(57) CLAIM

The ornamental design for a dish rack, as shown and described.

DESCRIPTION

FIG. 1 is a perspective view of a dish rack showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view showing a tray and a sorter coupled thereto.

The broken line portions of the dish rack in FIGS. 1-8 represent unclaimed portions of the claimed design and form no part thereof. The broken lines of the tray and the sorter in FIG. 8 illustrate unclaimed environment and forms no part of the claimed design.
